UNITED STATES PATENT OFFICE.

JOSEPH B. CLAY, OF CEDAR FALLS, IOWA.

CLOTHES-DRIER OR THE LIKE.

1,163,639.

Specification of Letters Patent. Patented Dec. 14, 1915.

Application filed August 18, 1913. Serial No. 785,397.

To all whom it may concern:

Be it known that I, JOSEPH B. CLAY, a citizen of the United States, residing at Cedar Falls, in the county of Blackhawk and State of Iowa, have invented certain new and useful Improvements in Clothes-Driers or the like, of which the following is a description.

My invention belongs to that general class of devices known as clothes driers, and relates particularly to a folding device particularly adapted for inserting in a suitable support for carrying clothes during the drying thereof, which device, after use, may be easily detached from the support, folded so as to occupy small space and stored until it is desired to use the same again.

The invention has among its objects the production of a light weight folding device of the kind described that is simple, convenient, durable, efficient, adjustable and satisfactory.

To this end my invention consists in the novel construction, arrangement and combination of parts herein shown and described, and more particularly pointed out in the claim.

In the drawings, wherein like reference characters indicate like or corresponding parts, Figure 1 is substantially a side elevation of the device and a sectional view of the support. Fig. 2 is an enlarged view of a portion of the device. Fig. 3 is a sectional view taken through the center of the device, and Fig. 4, is a sectional view taken substantially on line 4, 4 of Fig. 3.

Referring to the drawings, in which the preferred form of my device is shown, I represents an upright post, preferably constructed of tubular metal pipe, and arranged to carry a plurality of arms 2, which carry the clothes lines 3, the device being so constructed that the arms may be compactly folded against the post and the device stored in small space when not in use. Slidably and rotatably positioned on the post is a suitable part or collar 4, provided with ears 5, or the equivalent, to which the ends of the arms 2 may be pivotally secured by bolts 6, or their equivalents for the purpose.

Arranged on the post, preferably at the top, is a collar or cap 7, which is provided with a shoulder 8, so as to rest upon the top of and be supported by the upright post 1. The cap is also preferably provided with a closed top part 9, so as to keep water and

dirt from entering into the end of the pipe. The cap or collar 7 is preferably rotatably secured on the end of the post in a manner so that it may be easily detached, if so desired. As shown, it is provided with an internal groove 10 in the flanged portion 7, arranged to receive a pin 11, extending through the end of the post. The pin 11 is inserted through either of the holes 12 (see Fig. 4) and does not interfere with the rotation of the part 7 about the post.

The arms 2 are secured to the cap part 7 by brace bars or members 14, the same being pivotally secured in place by bolts 16, or the equivalent, to the arms, and by bolts 15 to the ears on the part 7. When the collar 4 is moved along the post away from the cap part 7, or as shown in the drawings, is dropped, the brace bars 14 draw the upper parts of the upper arms 2 up against the post, so that the device is very compactly folded. To open it the collar 4 is raised to the desired point, preferably until the lines 3 are taut. To maintain the collar 4 in the desired position, a latch member 17 is provided. The member 17 shown is secured to the upper cap or collar by a screw 18, or its equivalent, and provided at its free end with engaging faces 19, adapted to engage the flange or lip 20 on the part 4. The member 17 shown is made of resilient material and given a slight twist so as to bring the edge against the flange. Bearing faces or teeth 19 are preferably provided on member 17, so that some latitude is permitted in positioning the collar 4. As the line shrinks or stretches, the stretch or shrinkage may be taken care of by engaging the flange 20 at the proper tooth in the latch member 17. Any desired means may be provided to facilitate raising the collar 4 into engagement with the latch member 17. As shown, a forked lever 28 is carried by a wire 27, or its equivalent, from the post or from the upper cap. The end of the lever is forked as at 29 and arranged to embrace the post under the collar 4. Bearing down on the free end of the lever 28, raises the collar into engagement with the desired tooth on the latch member, or on the other hand facilitates releasing the latch, as the case may be. When not in use, the same may hang loose, substantially as shown in Fig. 1.

The lower end of the upright post may be supported in any desired manner. As shown, I preferably provide a post support

consisting of a concrete base part 23, adapted to be positioned in the ground G. If desired, a metallic lining 21 may also be arranged in the socket in the member and a vent 25 is provided for drainage, the same extending through the bottom of the socket to the lower end of the part. To close the socket when the drier is detached for storing, I preferably provide a cover or collar 22. As shown, this may be arranged so that it rests against the post 1 when the same is inserted in the socket, but falls of its own weight to close the socket when the post is removed. While, of course, the socket member may be set in any desired manner, it is preferably arranged so that it is slightly below the top of the ground, so that a lawn mower or the like may run over the socket without injury to the mower. The device being of exceeding light weight, it may be easily set up in position for use, and is easily folded and stored away, leaving the lawn free and clear and keeping the line clean until it is desired to use the same again.

Having thus described my invention, it is obvious that various immaterial modifications may be made in the same without departing from the spirit of my invention; hence I do not wish to be understood as limiting myself to the exact form, construc-

tion, arrangement or combination of parts herein shown and described, or uses mentioned.

What I claim as new and desire to secure by Letters Patent is:

In a clothes drier, the combination of an upright post, a collar part slidably arranged upon said post and rotatable thereabout, said collar provided with a flanged portion thereon, a cap part rotatably mounted on said post at the upper end thereof, means for detachably securing said cap in position, consisting of a detachable pin carried by said post with the ends of the pin projecting from each side of the post, said cap arranged for engagement with said pin at the ends thereof, a resilient latch member rigidly secured to said cap part and depending therefrom, said latch member provided with engaging faces arranged to cooperate with the flanged portion of said collar, and a plurality of arms pivotally secured to one part and provided with brace members connected to the other part.

In testimony whereof, I have hereunto signed my name in the presence of two subscribing witnesses.

JOSEPH B. CLAY.
